HERMAN R. FREUND, OF BROOKLYN, NEW YORK, ASSIGNOR TO INTERTYPE CORPORATION, OF BROOKLYN, NEW YORK, A CORPORATION OF NEW YORK.

MATRIX FOR TYPOGRAPHICAL MACHINES.

Application filed June 25, 1926. Serial No. 118,536.

The present invention relates to improvements in the matrices used in typographical machines of the general class shown and described in U. S. Patent No. 436,532, granted 5 September 16, 1890, wherein the matrices which bear in intaglio in their rear edges type-forming letters or characters, are assembled in a line and a type bar or slug is cast against its rear side, whereby a reproduction 10 of the type-forming characters of the matrices composing the line is obtained on the type bar.

It is usual to provide such matrices at their front edges with reference characters 15 which correspond with the type-forming characters in their rear edges, these reference characters being visible to the compositor, through the open front of the assembler frame or elevator in which the matrices are 20 commonly assembled into lines, and it is the usual practice of compositors to closely observe and constantly refer to these reference characters on the matrices while the latter are being assembled to form the lines 25 in order to verify the correctness thereof. This intense concentration of the vision of the compositor upon the reference characters on the matrices imposes a considerable burden upon the compositor's eyes, and his 30 eyes frequently become strained, fatigued, or otherwise affected injuriously under such intense observation when matrices as heretofore generally made are used.

It has been found that the eye strain or 35 fatigue frequently resulting from the use of ordinary matrices such as those heretofore used generally is due to the reflection of light from the compositor's lamp, which is usually placed above and in front of the 40 matrix line, back into the compositor's eyes, and that this objectionable reflection is caused by the mirror-like effect of bright colored minute scratches, grooves, or abrasions which extend transversely across the 45 front edges of the matrices and which are thus formed therein during polishing of these surfaces of the matrices, it having been heretofore the general practice, in view of manufacturing and other considerations, to 50 polish the front edges of the matrices by movement of the polishing tool or medium in a direction transversely across the edges of the matrices.

The object of the present invention is to 55 overcome this objection which is inherent in

matrices of this class as heretofore made, the front surface of the matrix embodying the present invention and which bears the reference character being so prepared that it precludes reflection of light therefrom into 60 the compositor's eyes, thereby enabling the compositor to concentrate his vision intensively on the reference characters in the front edges of the matrices for prolonged periods of composition without eyestrain or fatigue 65 or other injurious effects upon the compositor's eyes.

In the accompanying drawing:

Figure 1 is a front elevation of the matrix assembling elevator and adjacent parts of a 70 typographical machine of the general class hereinbefore referred to, showing a line of matrices in course of assemblage in the elevator and displaying the reference characters on their front edges. 75

Figure 2 is a front view of a matrix such as that heretofore used generally in machines of this class.

Figure 3 is a diagrammatic view illustrating the manner in which light rays from 80 the compositor's lamp is reflected from the front edge of such a matrix into the compositor's eyes.

Figure 4 is a diagrammatic view showing the front edge of an ordinary matrix on an 85 enlarged scale and illustrating the manner in which light from the compositor's lamp is reflected by the transversely extending scratches, grooves or abrasions in the front edge thereof. 90

Figure 5 is a front elevation of the improved matrix embodying the present invention.

Figure 6 is a diagrammatic view illustrating the manner in which light rays from 95 the compositor's lamp are reflected downwardly or in a direction away from the compositor's eyes by the improved matrix.

Figure 7 is a diagrammatic view showing the improved matrix on an enlarged scale 100 and illustrating the manner in which the light rays from the compositor's lamp are reflected downwardly.

In typographical machines of the general class hereinbefore referred to, the matrices are assembled successively in a frame or so-called assembling elevator 10, the matrices which are stored in magazines being released therefrom by manipulation of the usual keyboard by the compositor, the released mat- 105 110

rices being delivered by a belt, part of which is shown, to a star-wheel 11 which operates to stack the matrices successively to form the line in the assembling elevator. Each matrix comprises a body 12, the rear edge 13 of which has a die cavity 14 therein which embodies a type-forming letter or character in intaglio, it being well understood in this art that a cast is made against the rear face of each line of assembled matrices, after the line has been justified in the well known way, whereby a type bar is obtained an edge of which bears type characters corresponding with the type-forming characters in the rear edges of the matrices composing the line. The front edge 15 of each matrix usually has a reference character 16 stamped or similarly formed therein, the reference character in the front edge of each matrix corresponding with the type-forming character in its rear edge, and the reference characters on the matrices are visible through the open front of the assembling elevator during the composition of each line, as will be seen from Figure 1. In practice, the compositor constantly refers to the reading line formed on the front edges of the matrices and to the reference characters on the individual matrices during the course of composition of each line, in order to determine the correctness of the composition thereof, and in order to render these reference characters visible to the compositor a lamp 17, usually known as the compositor's lamp, is placed on the front of the machine at a height above the level at which the matrices are assembled to form the lines, this lamp being usually provided with a reflector 18 which focuses or directs light rays from the lamp onto the front edges of the matrices in the line. The compositor's position at the keyboard of the machine is such that his eyes are normally at a level above that at which the matrix lines are assembled, E in Figures 3 and 6 representing diagrammatically the approximate normal position of the compositor's eyes relatively to the lamp and the matrix line in course of composition.

It has been found that the composition of matrices such as those heretofore used in machines of this class, the eyes of the compositor became strained or fatigued, or otherwise injuriously affected by light rays of considerable intensity which are reflected from the front edges of the matrices in the assembling elevator while the line is in course of composition. The path of these light rays when ordinary matrices are used is illustrated diagrammatically in Figure 3, A representing the light rays passing from the lamp 13 to the front edge of the matrix and A' representing the reflected rays which proceed from the front edge to the eyes of the compositor. It has also been found that the reflection of these light rays from the front

edge of the matrix upwardly to the eyes of the compositor is due to the presence of a great number of scratches, grooves or abrasions which are represented on an enlarged or exaggerated scale in Figure 4 and designated "X" thereon. These scratches, grooves or abrasions extend horizontally or transversely across the front edges of the matrices and those walls of the scratches, grooves or abrasions which slope in a direction forwardly and downwardly act, in effect, as mirrors which reflect the light rays a from the lamp in a direction upwardly and forwardly or in the path b so that these reflected rays strike the eyes of the compositor. The light rays are thus reflected into the compositor's eyes from the mirror or reflector surfaces of the scratches, grooves or abrasions in accordance with the law that the angle of reflection equals the angle of incidence. These scratches, grooves or abrasions which extend horizontally or transversely across the front edges of the matrices are produced during the polishing of these edges of the matrices, it being common practice heretofore to polish these edges of the matrices by movement of the polishing tool or medium in a direction transversely of these edges of the matrices, in view of manufacturing and other considerations.

The present invention enables matrices of this general class to be manufactured by the methods heretofore used generally, with the exception of the mode of polishing the front edges of the matrices, these front edges of the matrices, according to the present invention, being so polished as to preclude the objectionable reflection of light therefrom into the eyes of the compositor. According to the present invention, the front edges of the matrices are polished by movement of the polishing tool or medium in a direction longitudinally of the front edges of the matrices and, hence, no horizontal or transversely extending scratches, grooves or abrasions will be formed in this edge of the matrices, but, on the contrary, any resulting scratches, grooves or abrasions will extend longitudinally or vertically of the front edges. In consequence, when matrices made in this way are assembled in the assembling elevator, the light rays A from the compositor's lamp and which are directed downwardly and rearwardly to the front edges of the matrices in the assembling elevator will be reflected in a downward and forward direction as indicated at C in Figure 6, in accordance with the law that the angle of reflection is equal to the angle of incidence. The light from the lamp reflected from the front edges of the matrices is thus directed away from the compositor's eyes and, hence, eye-strain or fatigue or other injurious effects resulting from the use of ordinary matrices as heretofore made, is avoided. In Figure 7, which

represents diagrammatically the front character-bearing edge of the improved matrix, a represents any given light ray passing from the compositor's lamp to the front edge of the matrix, and α indicates the angle at which such ray is reflected by this surface of the matrix. Any scratches, grooves or abrasions that may be present in the front edge of the improved matrix will extend vertically or substantially so therein and such scratches, grooves or abrasions would reflect the light rays from the compositor's lamp more or less laterally as well as downwardly, but the downward reflection of the light rays precludes such rays from reaching the compositor's eyes.

I claim as my invention:—

1. A matrix for typographical machines having a front reference-character-bearing edge which is polished longitudinally thereof.

2. A matrix for typographical machines having a polished front reference-character-

bearing edge which is devoid of polishing abrasions extending transversely thereof. 25

3. A matrix for typographical machines having a polished front reference-character-bearing edge the polishing abrasions in which extend longitudinally only in said edge.

4. A matrix for typographical machines having a polished front reference-character-bearing edge which presents a continuous plane surface longitudinally thereof whereby all light rays striking said surface from above it will be reflected downwardly therefrom. 35

5. The improvement in the art of manufacturing matrices for typographical machines which comprises polishing the front 40 character-bearing edge of a matrix by movement of the polishing medium in a direction longitudinally of said edge.

In testimony whereof I have hereunto set my hand.

HERMAN R. FREUND.
